US0D1109020S

(12) **United States Design Patent** (10) **Patent No.:** **US D1,109,020 S**
(45) **Date of Patent:** **** Jan. 13, 2026**

(54) **ELECTRIC BICYCLE**

(71) Applicant: **Huizhou Aobang Technology Co., LTD**, Guangdong (CN)

(72) Inventor: **Yanlei Feng**, Guangdong (CN)

(73) Assignee: **Huizhou Aobang Technology Co., LTD**, Guangdong (CN)

(**) Term: **15 Years**

(21) Appl. No.: **29/947,811**

(22) Filed: **Jun. 18, 2024**

(30) **Foreign Application Priority Data**

May 31, 2024 (CN) 202430330378.2

(51) **LOC (15) Cl.** **12-11**

Michael Bartholomew

(57) **CLAIM**

The ornamental design for an electric bicycle as shown and described.

DESCRIPTION

FIG. 1 is a top-front-left side perspective view of an electric bicycle embodying my new design;

FIG. 2 is a bottom-rear-right side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The dashed broken lines depict portions of the electric bicycle that form no part of the claimed design.

1 Claim, 8 Drawing Sheets
